SORTING MACHINE

Harold H. Snyder, Mount Lebanon, Pa., assignor
to Forter-Teichmann Company, Pittsburgh,
Pa., a corporation of Pennsylvania

Application September 10, 1942, Serial No. 457,805

17 Claims. (Cl. 209—75)

This invention relates to sorting machinery, and consists in a machine adapted to sort by size and weight the product of glass tube making procedure. It finds practical application in the sorting of tubes that are produced for incandescent-vapor lamps. The object in view is facile and accurate sorting.

In the accompanying drawings Fig. I is a fragmentary view of the machine, seen in side elevation; Fig. II is a view of the machine in plan; Fig. III is a view to somewhat larger scale, showing the machine in end elevation, as seen from the left, Figs. I and II. The remaining figures show to much larger scale details of machine structure. Fig. IV shows, partly in vertical section and partly in side elevation and in assembly with the supporting chain, a tube-moving abutment and a cooperating jaw; Fig. V shows the same assembly in vertical and transverse section. The pair of jaws is here seen in front elevation—from the right, Fig. IV. Figs. VI and VII show, partly in vertical and longitudinal section, partly in side elevation, one of the jaw-opening devices and one of the gravity-operating escapes for the ware; and Figs. VIII and IX show partly in vertical and longitudinal section and partly in side elevation a detail of the transmission mechanism by which the machine is driven and, in association therewith, certain control apparatus.

The machine is of table-like character, and includes a frame 1, and a fragmentary and discontinuous top made up of stationary plates 2 and movable plates 3. The plates 2 extend in common horizontal plane; they are arranged in two lines or rows; the rows are spaced widely apart, transversely of the machine; and, within each row, the successive plates are spaced at narrow intervals from one another. The plates 2 in the two rows are arranged in opposite pairs. The movable plates 3 extend normally in common plane with the plates 2; they also are arranged in two lines or rows; the rows are spaced less widely apart than the rows of plates 2, and the two rows of plates 3 are arranged in the interval between the rows of plates 2. The plates 3 in their two rows are arranged in opposite pairs; and the plates 3 bridge the intervals at which the plates 2 within their rows stand apart. The effect is that the tubes to be sorted, lying transversely upon the table, are advanced singly from right to left, Figs. I and II, and, as they so advance, they rest alternately at their ends upon plates 2, and at less widely spaced portions upon

plates 3. The plates 3 are mounted to swing vertically downward from their normal positions of coincidence with the plane of the table-top, and they are counterweighted to continue normally in such position. It is under the weight of a tube resting upon them that a pair of plates 3 will swing and allow the tube to descend through the table-top to the receptacle prepared for it.

Above this fragmentary and discontinuous table-top work-advancing mechanism is arranged. 10 Upon suitable standards at the two ends of the table-top two pairs of sprocket-wheels 4 are rotatably mounted, and upon the two pairs of sprocket-wheels two identical endless chains 5 are trained. The two chains extend in upper 15 and lower parallel and horizontal reaches, and the planes of the two reaches are both of them above the plane of the table-top itself.

A motor 6 is mounted in the frame 1 of the machine, and from the motor a horizontally disposed disk 7 borne by a vertical shaft is constantly rotated. A slide 8 (cf. Fig. VIII), reciprocable in ways 9 that are mounted upon and extend longitudinally of the frame, bears a stud 10 that enters and is engaged by a cam groove 20 formed in the nether face of the disk 7; and, by proper shaping of the cam groove, reciprocation of the slide through a suitable range and at suitable acceleration is effected in response to 25 rotation of the disk. The slide 8 carries a rack 11; and through the rack-and-pinion connection generally indicated at 12, Fig. VIII, reciprocation of the horizontally extending slide 8 imparts reciprocation to a vertically extending rod 13. A 30 rack-and-pinion drive 14 is arranged between the rod 13 and the shaft upon which the sprocket wheels 4 to the left, Fig. I, are rigidly borne. The drive 14 includes the familiar clutch, effective in one direction only, whereby reciprocation 35 of the rod 13 in one direction effects rotation of the sprocket wheels, while the return reciprocation of the rod is ineffective. As seen in Fig. I, it is the downward travel of the rod 13 that effects the turning of the immediately associated 40 sprocket-wheels 4; the wheels turn in clockwise direction; and the stress of traction is exerted upon the chains at the left-hand end of their lower reach. By such means the constant rotation of disk 7 effects intermittent and step-by-step advance of the two sprocket chains, and in 45 the direction indicated.

The chains are equipped, each with a succession of abutments 50 that extend from the chains upon one side thereof. The abutments upon the two chains are arranged oppositely in pairs.

These abutments, engaging the work from behind, carry it forward in right-to-left course (Figs. I and II, VI and VII), while it rests upon the table-top composed of plates 2 and 3. Cooperating with each abutment 15 is a jaw 16 that, in the range of chain travel, closes upon abutment 15 to retain a length of tube placed between, and recedes from the abutment to allow the length of tube to escape. The jaw is arranged in advance of the abutment; that is to say, it opens and closes upon the face of the abutment that in chain travel is the leading face. In Fig. IV the jaw 16 is shown in full lines in closed position upon abutment 15, and in dotted lines in open position. In Fig. VI the jaws are shown in closed position upon two abutments; and in Fig. VII a jaw is shown in open position. Referring to Fig. I, it will be seen that as the chains ascend, rounding the sprocket-wheels to the left, the jaws 16 are open; and it may be understood that it is at that point in chain travel that the lengths of tube to be sorted are placed, one by one, between an abutment 15 and the adjacent and cooperating jaw. As the abutments advance from the sprocket-wheels on the left along the upper horizontal reach of chain travel, the jaws close, and in so doing secure the lengths of tube, until in the course of advance from right to left along the lower horizontal reach of chain travel, the jaws are, by means provided to that end, automatically opened. Referring to Figs. I, IV, and V, it will be seen that the jaw 16 is pivoted in the body of the chain-borne abutment 15 (cf. Fig. IV). A spring 18 is so arranged between abutment and jaw that, whether the jaw be closed or open, it tends to hold the jaw in the position to which it has come (cf. Figs. VI and VII). The spring 18 is anchored to the jaw 16 by a post 180 that extends laterally, clear of immediately adjacent parts. Turning to Fig. I, block 181 will be seen, rigidly borne upon the frame of the machine. The block has an inclined upper face, and it will be perceived that by the engagement of the pin 180 with the abutment 15, the advancing jaws 16 will one-by-one be swung from open (broken-line position, Fig. IV), to closed (full-line position).

A bolt 17 is telescopically borne by the body of the abutment 15, and extends from the supporting chain 5 on the side opposite that from which the abutment itself extends. This bolt engages the jaw 16, as by the tongue-and-groove engagement shown, with the effect that the closing of the jaw causes the bolt to be extended, and the inward shifting of the bolt causes the jaw to open.

As the articles advance above the table-top from right to left, Figs. I, II, VI, and VII, in the lower horizontal reach of chain travel, they are sorted both by size and by weight.

The devices for sorting by size are provided in pairs, corresponding to the pairs of abutments 15 with which the chains 5 are equipped; and there is a plurality of pairs, situated at successive points in the line of advance of the chains through their lower horizontal reach. The size-sorting devices are duplicates one of another, though adjusted differently, so as to act selectively.

With Figs. VI and VII in view, each size-sorting device may be seen to include a casing 19, within which a power-transmission member in the form of two crank-disks 20 and 21, integrated together, are rotatably borne. A bell-crank lever 22, mounted upon a stationary fulcrum and adapted to swing in vertical plane, and a verti-

cally arranged bolt 23, extensible and retractible in casing 19, are interconnected through the power-transmission member. The power-transmission member is provided peripherally with 5 adjacent notches 24, 25; and a ball 26, mounted in casing 19 and backed by a spring 27, engaging these notches in alteration, tends to shift the power-transmission member when in intermediate position in its range of turning and to advance it to the end of its range and hold it there. The power arm of the bell-crank lever is equipped with an adjustable bearing-block 28.

A further refinement is found in disks 29, rotatable each upon a stationary axis, that rise 15 slightly above the general level of the table-top. Over these disks the tube-lengths are impelled, and upon them they rest at the instant when they come beneath the bearing-blocks 28.

This device is so arranged that the bolt 23 advances into and recedes from the path of progress of the abutment-borne bolt 17; and the bearing-block 28 is disposed above and at a carefully adjusted space interval from the plane of the table-top.

In operation (referring particularly to Fig. VI) the chains 5, advancing from right to left, carry successive lengths T of tubing above the table-top and through the size-sorting device. The bearing-block 28 is so carefully adjusted in its 30 position that if the advancing tube be of less than a critical diameter, it will pass freely through the sorting device, without effecting operation of the sorting device. Such a small and ineffective tube is shown in full lines to the 35 left in Fig. VI. In this same figure, in full lines to the right, a tube of larger size and of size adequate to effect the operation of the sorting device is shown. This tube, advancing from right to left, comes to the broken-line position 40 shown, and in its advance, having engaged block 28, it swings bell-crank lever 22 clockwise from full-line to broken-line position. Such shifting of the bell-crank lever effects, with the aid of the spring-backed ball 26, the extension of the 45 bolt 23 to the dotted-line position. The continued progress of the chain-borne abutment 15 then brings bolt 17 to engagement with bolt 23. Both bolts are retractible vertically; their meeting faces are properly rounded. The tension of 50 spring 27 is exerted upon bolt 23, tending to hold it in its extended position; the tension of spring 18 is exerted with like effect upon bolt 17. The two springs are so proportioned to one another that it is spring 18 which first yields, and with 55 the effect that jaw 16 is swung clockwise and the parts come to the position shown in Fig. VII. The length of tubing is released and rests upon the table-top. The jaw 16 is now held in open 60 position by the tension of spring 18, and, in the continued right-to-left progress of abutment 15 the length T of tubing, resting freely upon the table-top, advances upon the table-top.

In the further right-to-left progress of abutment 15 the bolt 17, having now reached the end 65 of its downward traverse, continues to be effective in forcing bolt 23 upward, and it is so effective until the spring-backed ball 26, having crossed the interval that separates the notches, enters notch 24 and shifts bolt 23, transmission member 20, 21, and bell-crank lever 22 back to the Fig. VI positions. Thus the sorting device, 70 having operated upon one of the advancing tube lengths, is automatically made ready for operation upon the next one.

The crank-disks 20 and 21 are mounted on a

shaft 200, and this shaft extends between the two sorting devices of the pair, so that both devices operate in unison, insuring that both of the jaws 16 engaging a tube-length will open together. It will thus be seen that, if a tube-length in progress through the machine, should not be of uniform diameter, and if the diameter of the tube should at one end only exceed the critical value, both of the jaws 16 will open and the tube-length will be released.

Referring now to Figs. I and II, it is to be remarked that, considering the table-top from right to left, the space interval between the first pair of plates 2 is not bridged (as are succeeding intervals) by plates 3; that, in transverse alignment with the first pair of plates 2, is set a pair of size-sorting devices S', and, in transverse alignment with the second pair of plates 2, is set a second pair of size-sorting devices S². Let it be understood that the blocks 28 of the sorting devices S' are so particularly adjusted as to be operated by a tube-length of diameter exceeding x , and let it be understood that the blocks 28 of the sorting devices S² are so adjusted as to be operated by a tube-length of diameter x as a maximum and $x-a$ as a minimum. As the succession of tube-lengths advances through the two pairs of sorting devices, all of the lengths of excessive diameter, released by the opening of the jaws of the first pair of sorting devices, will fall through the space interval at which the plates 2 of the first two pairs stand apart, and may be received in a bin 30; all of the tube-lengths of diameters ranging from x to $x-a$ will, as they pass through the second pair of sorting devices S², S², be released by the swing of the jaws 16, to rest upon the plates 3, and to be advanced over the table-top as the abutments 15 advance; while the tube-lengths of diameter less than $x-a$ will pass through the sorting devices S², S² with no shifting of the jaws 16, and they will be carried forward above the table-top sustained by the still closed jaws.

A tube-length released by the sorting devices S², S² rests immediately upon plates 3. The plates 3 are secured to disks 31 borne by a shaft 32 (the shaft that carries disks 29 also. See Fig. III), and shaft 32 is rotatably mounted in the frame of the machine. The shaft 32 carries a drum 33 upon which the suspension cord 34 of a weight 35 is by the turning of the shaft wound and unwound. Referring again to Fig. VII, as the tube-length T resting free upon the plate 3 is by the advance of abutment 15 carried along the plate from a position near to the axis of turning to a position far from the axis of turning, its weight becomes increasingly effective; and, by exceeding a value that is predetermined by the actual value of weight 35, it will swing the plate 3 counter-clockwise, from the full-line position (Fig. VII) to the broken-line position, and in so doing will itself roll from the sloping plate and descend to the receptacle 42 provided for its reception. The weight 35 then will be effective to swing the plate 3 again to its normal position in the plane of the table-top.

A stop 37 is provided, engaged by a pin 38 that extends from drum 33, limiting the clockwise turning of the shaft 32 to the point at which the plates 3 lie in the plane of the table-top. A pin 39 extends from drum 33 and enters a slot 40 in a slide 41. The chains 5, as has already been explained, advance intermittently, in step-by-step course; and (referring to Figs. I, VIII, and IX), it is on the down-stroke of the stem 13 that the

chains advance. As the stroke is approaching completion, the slide 41 is, through the instrumentalities clearly indicated in Figs. VIII and IX, shifted from left to right, and the shaft is released to turn under the weight of the tube-length. The organization is such that when the stem 13 has so completed its down-stroke, the tube-length T has reached the left ends (Fig. VII) of the plates 3. In the ensuing up-stroke of the stem 13 the slide 41 is shifted from right to left. It is important thus to control the shifting of the slide 41, to the end that the two plates 3 upon which a tube-length is borne shall be released to swing simultaneously. The lost motion in the line of transmission between stem 13 and slide 41, clearly shown in Figs. VIII and IX, has effect that the slide is shifted as the abutments 15 approach the end of their successive steps of advance, allowing the plates 3 to make their unloading and return swing before the interval of rest comes to an end and the abutments 15 begin the next step of their advance.

The operation of the gravity-sorting device is as follows:

At the time when a work-advancing step in chain movement begins, the pin 38 is bearing upon the stop 37 and pin 39 is bearing upon the right-hand end of slot 40 in slide 41 (cf. Fig. VIII). The shaft 32 then is positively restrained against rotation in either direction, and the plate 3 is held rigidly in horizontal position. The shaft and plate remain so restrained until the chains, in their advance have carried a tube-length almost to the distal end of the plate 3. Thereupon, the slide 41 is by the instrumentalities described shifted in left-to-right direction, and (the weight of the tube-length exceeding in effect the weight 35) the shaft 32 is turned counter-clockwise (Fig. VII) and the plate 3 is swung from full-line to broken-line position. This movement is controlled and limited by the continued bearing of pin 39 upon the right-hand end of the slot in the shifting slide 41. The tube-length drops from the downwardly tilted plate, and rolls down rails 36 into the receptacle 42. It will be perceived that the slide 41 regulates the rate and extent of tilting of the plate 3 into tube-releasing position, and it will be manifest that such controlled and smooth operation of the mechanism is desirable in the sorting of the glass articles here in contemplation.

The parts are so organized that as the slide 41 reaches the end of its left-to-right movement, a step in chain-advance is completed. And while the chains remain at rest the rod 13 (Fig. VIII) makes its idle up-stroke and the plate 3 returns to horizontal position. When the tube-length drops from the tilted plate 3, the weight 35 is effective immediately to turn the shaft 32 and plate 3 clockwise, bringing the pin 39 to abutment upon the left-hand end of the slot in slide 41. As the stem 13 approaches the end of its up-stroke it drives the slide in its opposite right-to-left course, and (the pin 39 held by the effect of weight 35 against the left end of slot 40), the parts gradually return to their original positions. When the pin 38 engages the stop 37 and arrests the shaft 32, the plate 3 has come again to the plane of the table-top. The slide 41 continues its right-to-left movement until the right-hand end of slot 40 comes to abutment upon the pin 39, thus locking the plate 3 in the plane of the table-top.

With the attention upon Figs. I and II, it will be remarked that, including the pair of plates 3 immediately associated with the pair of sorting

devices S^2 , S^2 , there are ten pairs of plates 3 in right-to-left sequence; and it may be understood that, by giving diminishing values to the weights 35 that determine the tube weight effective to swing the plates 3 , the tube-lengths that, by the operation of the sorting devices S^2 , S^2 have been released from confinement of the jaws 16 , may be graded by weight and segregated in the succession of receptacles 42 . Beyond and to the left of the last of the ten pairs of plates 3 that have just been designated, the next succeeding interval between plates 2 , 2 is not bridged; and any tube-length of diameter between x and $x-a$, too light to swing the last pair of plates 3 in such sequence of ten, will fall through such interval to be caught in a receptacle 43 . It may be understood that for a given tube diameter there is a corresponding minimum weight; and, accordingly, the means specified are effective, after culling out and grading the tube-lengths of useful size and weight, to gather for rejection the tube-lengths that do not come up to specification.

Explanation has been given above that, while sorting devices S^2 , S^2 are effective to release tube-lengths that range in diameter from x to $x-a$, they are ineffective to release tube-lengths of diameter less than $x-a$. These are carried by the chains 5 , secured by the closed jaws 16 , over the succession of ten plates 3 alluded to above and across the interval between succeeding pairs of plates 2 , 2 , through which tube-lengths of larger diameter (released from the retentive jaws 16) fall to receptacle 43 . The table-top is continued to the left, and, immediately to the left of the interval last alluded to, yet another pair of size-sorting devices S^3 , S^3 is set. This pair of sorting devices may be understood to be effective to release all tube-lengths of a diameter less than $x-a$ and down to a diameter of $x-a-b$. The succession of pairs of plates 3 from the sorting devices S^3 , S^3 to the left, properly weighted, cooperates with the sorting devices S^3 , S^3 precisely as the ten pairs of plates described above cooperate with the devices S^2 , S^2 . The devices S^3 , S^3 leave still secured by jaws 16 all tube-lengths of diameter less than $x-a-b$; and the immediately adjacent succession of plates 3 , terminating with a blank and unbridged interval between successive pairs of plates 2 accomplish the sorting by weight and the disposal of all tube-lengths of diameter ranging less than $x-a$, down to $x-a-b$. Beyond the sorting devices S^3 , S^3 and the associated table-top parts, yet another pair of size-sorting devices S^4 , S^4 may be placed, effective to release all chain-borne tube-lengths of diameter less than $x-a-b$, and the succeeding table-top members may be made effective in the manner described to sort by weight the so released tube-lengths. Manifestly, the number of pairs of size-sorting devices S^2 , S^3 , S^4 and associated table-top parts may be increased or diminished, to meet the condition of the tube-lengths to be sorted and the requirements of use.

In case certain of the tube-lengths introduced to the machine are smaller in diameter than the minimum required to operate the last pair of sorting devices S^4 , S^4 , the paired jaws 16 that embrace such tube-length will remain closed throughout the traversal of the table-top, but at the end of such traversal these jaws (and all other unopened jaws, too) are by the engagement of jaw-operating stems 17 with a cam plate 170 (Figs. I and III) opened, and the tube-length released to fall into receptacle 44 .

The tube-lengths to be sorted are placed one

by one between the succeeding pairs of abutments 15 and the cooperating and open jaws 16 as the chains 5 advance through their upward rounded course at the left-hand end of the machine, as seen in Fig. I, and to the abutments 15 ; engagement of the pins 18 of the succeeding jaws 16 effects the closing of the jaws upon the so placed articles. These articles, carried by the chains, advance throughout the progress of chain travel until, in the lower, right-to-left reach of chain travel, the size-sorting devices, S^1 , S^2 , S^3 , etc. effect the release of the articles in segregated groups, and either immediately, or through the selective action of counterweighted plates 3 , the unsuitable articles are culled out and the suitable ones within each group are graded by weight and segregated.

The machine is applicable in the grading of tubes that vary in diameter and weight, regardless of material and regardless of intended use.

From what has been said, it will be understood that the points at which the devices S^1 , S^2 , S^3 , S^4 , etc., are located may be considered size-grading stations; that the machine therefore comprises a succession of spaced-apart size-grading stations; and that in the intervals between the successive stations the members 3 , 3 provide a series of spaced-apart gravity sorting devices, with a stationary support 2 , 2 arranged in each of the spaces between such gravity sorting devices. The devices S^1 , S^2 , S^3 and S^4 selectively release the tubes (advanced by the conveyor 5 , 5) according to size to one or another of the series of gravity sorting devices. The gravity sorting devices are graduated in weight-grading effect, whereby each tube released to a particular series is selectively discharged according to its weight.

I claim as my invention:

1. A machine for assorting articles according to size and weight comprising succession of spaced-apart size-grading stations, a series of spaced-apart gravity sorting devices organized with each station and with the several series arranged sequentially with respect to said stations, means for engaging and transporting articles to be assorted sequentially through said stations and the intervening series of sorting devices, and means at each station for releasing the articles according to size to one or another of said series of gravity sorting devices.

2. A tube-sorting machine that includes a table-top, a plurality of abutments movable above and longitudinally of the table-top and adapted in their progress to advance one by one a succession of tube-lengths resting on the table-top, a movable jaw associated with each abutment adapted in its range of movement alternately to secure a tube-length to the abutment in a position spaced above the plane of the table-top and to release a so secured tube-length, allowing it to descend and to rest upon the table-top, a jaw-opening device arranged adjacent the table-top, operable by engagement with it of an advancing jaw-held tube-length of a diameter exceeding a predetermined minimum, the table being equipped with gravity-sorting means.

3. A tube-sorting machine that includes a table-top consisting of two spaced-apart rows of stationary plates extending in common plane, the plates of the two rows being arranged in opposite pairs with spaces between the pairs, a succession of movable and counterweighted bridge-plates spanning a succession of intervals between the pairs of stationary plates, the counterweighting being of decreasing magnitude throughout

the succession, a plurality of abutments movable over the table-top in the direction of the succession of bridge-plates and from the more heavily counterweighted to the less heavily counterweighted plates and adapted to advance a succession of tube-lengths one by one over the table-top, a movable jaw associated with each abutment and adapted in its range of movement alternately to secure a tube-length to the abutment in a position spaced above the plane of the table-top and to release a so secured tube-length, allowing it to descend and to rest upon the table-top, and a jaw-opening device arranged adjacent the table-top and adjacent that end of the succession of bridge-plates at which the abutment-borne tube-lengths approach the succession of bridge plates, said jaw-opening device being operable by the advance of a jaw-held tube-length of a diameter exceeding a predetermined minimum.

4. A tube-sorting machine that includes a table-top, a plurality of abutments movable above and longitudinally of the table-top and adapted in their progress to advance one by one a succession of tube-lengths resting on the table-top, a movable jaw associated with each abutment and adapted in its range of movement alternately to secure a tube-length to the abutment in a position spaced above the plane of the table-top and to release a so secured tube-length, allowing it to descend and to rest upon the table-top, a plurality of jaw-opening devices arranged adjacent the table-top and standing spaced apart at intervals in the direction of abutment advance, the said jaw-opening devices being operable by engagement with it of an advancing jaw-held tube-length, one of the devices being operable by a tube-length of a diameter exceeding a predetermined minimum, and another device, standing second in the direction of abutment advance, being operable by a tube-length of a diameter less than such minimum, the table being equipped with gravity-sorting means.

5. A tube-sorting machine that includes a table-top consisting of two spaced-apart rows of stationary plates extending in common plane, the plates of the two rows being arranged in opposite pairs with spaces between the pairs, a succession of movable and counterweighted bridge-plates spanning successive intervals between the pairs of stationary plates, the bridge-plates formed into a plurality of successive groups by counterweighting of diminishing value from the first plate of the group in the direction of the succession, a plurality of abutments movable over the table-top in the direction of the succession of the bridge-plates and in the direction from the more heavily to the less heavily counterweighted plates within each group, a movable jaw associated with each abutment and adapted in its range of movement alternately to secure a tube-length to the abutment in a position spaced above the plane of the table-top and to release a so secured tube-length, allowing it to descend and to rest upon the table-top, and a plurality of jaw-opening devices arranged adjacent the table-top and standing spaced apart at intervals in the direction of abutment advance, one adjacent the head of each of the groups of bridge-plates, the said jaw-opening devices being operable by the advance of jaw-held tube-lengths, one of the devices being operable by the advance of a tube-length of a diameter exceeding a predetermined minimum, and another device, standing second in the direction of abutment advance, being operable by the ad-

vance of a tube-length of a diameter less than such minimum.

6. A tube-sorting machine that includes a table-top consisting of two spaced-apart rows of stationary plates extending in common plane, the plates of the two rows being arranged in opposite pairs with spaces between the pairs, movable and counterweighted bridge-plates spanning intervals between pairs of stationary plates and arranged in a plurality of groups, the plates within each group spanning successive intervals and the groups being separated by an interval between pairs of stationary plates that is unbridged, the counterweighting within each group being of decreasing magnitude from the remote end of the succession toward such an unbridged interval, a plurality of abutments movable over the table-top in the direction of the successions of bridge-plates and in the direction from the more heavily toward the less heavily counterweighted bridge-plates within each group, a movable jaw associated with each abutment and adapted in its range of movement alternately to secure a tube-length to the abutment in a position spaced above the plane of the table-top and to release a so secured tube-length, allowing it to descend and to rest upon the table-top, and a plurality of jaw-opening devices arranged adjacent the table-top and standing spaced apart at intervals in the direction of abutment advance, one arranged adjacent the most heavily counterweighted bridge-plate of each group, the said jaw-opening devices being operable by the advance of jaw-held tube-lengths, one of the devices being operable by the advance of a tube-length of a diameter exceeding a predetermined minimum, and another device, standing second in the direction of abutment advance, being operable by the advance of a tube-length of a diameter less than such minimum.

7. The structure of claim 2, together with jaw-closing means adapted to cooperate with the successive jaws as the abutments advance toward the jaw-opening device.

8. The structure of claim 2, the abutment being equipped with an extensible and retractible bolt and the jaw-opening device being equipped with an extensible and retractible bolt, the two bolts in the progress of operation moving to and from positions of axial alignment, yielding means associated with each bolt and tending to hold the bolt in extended position, the parts being so proportioned that by interengagement of the bolts the abutment-borne bolt is first retracted and the bolt borne by the jaw-opening device is retracted in sequence thereafter.

9. The structure of claim 2, the abutment being equipped with an extensible and retractible bolt and the jaw-opening device being equipped with an extensible and contractible bolt, the two bolts in the progress of operation moving to and from positions of axial alignment, yielding means associated with each bolt and tending to hold the bolt in extended position, the parts being so proportioned that by inter-engagement of the bolts the abutment-borne bolt is first retracted and the bolt borne by the jaw-opening device is retracted in sequence thereafter, and bolt-extending means operative upon the last-named bolt and made effective on the partial retraction of the last-named bolt.

10. In glass tube sorting machinery, and in combination with a table-top equipped with gravity-sorting elements a carrier, a plurality of abutments borne by the carrier and adapted to effect the advance of tube-lengths one by one

75

over the table-top, a jaw associated with each such abutment and on the advance side of the abutment and pivoted to swing between work-holding and work-releasing positions relatively to the abutment, means adapted to hold the jaw alternately in open and closed position, means arranged adjacent the path of carrier advance at a point remote from the table-top rendered effective by engagement of the jaw therewith and adapted to effect the swing of the jaw from open to closed position, and means adjacent the path of carrier advance and adjacent the table-top rendered effective by engagement with it of a jaw-held length of tubing adapted to effect the swing of the jaw from closed to open position.

11. A machine for assorting articles according to size and weight comprising a succession of spaced-apart size-grading stations and a series of spaced-apart gravity sorting devices organized with each station and with the several series arranged sequentially with respect to said stations, stationary supports arranged in the intervals between said devices in each series, means for engaging and transporting articles in succession from station to station in the machine, and means organized at each station and operating according to the size of the transported articles to release the articles to the effect of one or another of said series of gravity sorting devices.

12. A machine for assorting articles according to size and weight comprising a succession of spaced-apart size-grading stations and a series of spaced-apart gravity sorting devices organized with each station and with the several series arranged sequentially with respect to said stations, stationary supports arranged in the intervals between said devices in each series, means for engaging and transporting articles in succession from station to station in the machine, and means organized at each station and operating according to the size of the transported articles to release the articles to the effect of one or another of said series of gravity sorting devices, together with receptacles for the assorted articles arranged severally with the gravity sorting devices of each series.

13. A machine for assorting tubes or other elongate articles according to size and weight comprising a succession of spaced-apart size-grading stations and a series of spaced-apart gravity sorting devices between each of said stations and the next station in the succession, with stationary supports arranged in the intervals between said devices, means for engaging each of said tubes at spaced-apart points and transporting the tubes in succession from station to station in the machine, and means at each station that operate selectively to release the engaged articles according to their external diameters to the weight-grading effect of one or another of said series of gravity sorting devices.

14. A machine for assorting tubes or other elongate articles according to size and weight comprising a succession of spaced-apart size-grading stations and a series of spaced-apart gravity sorting devices between each of said stations and the next station in the succession, with

stationary supports arranged in the intervals between said devices, means for engaging each of said tubes at spaced-apart points and transporting the tubes in succession from station to station in the machine, and means at each station that operate selectively to release the engaged articles according to their external diameters to the weight-grading effect of one or another of said series of gravity sorting devices, and receptacles arranged with said gravity sorting devices severally.

15. A machine for assorting tubes or other elongate articles according to size and weight comprising a succession of spaced-apart size-grading stations and a series of spaced-apart gravity sorting devices between each of said stations and the next station in the succession, with stationary supports arranged in the intervals between said devices, means for engaging each of said tubes at spaced-apart points and transporting the tubes in succession from station to station in the machine, and means at each station that operate selectively to release the engaged articles according to their external diameters to the weight-grading effect of one or another of said series of gravity sorting devices, each of said gravity sorting devices comprising a rotatably mounted shaft upon which a plate is borne, a weight hung from the shaft and tending to rotate the shaft under gravity, a stop limiting the rotation of the shaft, and means for controlling the turning of the said shaft, such means including a member reciprocated by the tube-engaging and transporting means and in coordination with the movement thereof.

16. A machine for assorting tubes or other elongate articles according to size and weight comprising a succession of spaced-apart size-grading stations and a series of spaced-apart gravity sorting devices between each of said stations and the next station in the succession, with stationary supports arranged in the intervals between said devices, means for engaging each of said tubes at spaced-apart points and transporting the tubes in succession from station to station in the machine, and means at each station that operate selectively to release the engaged articles according to their external diameters to the weight-grading effect of one or another of said series of gravity sorting devices, each of said gravity sorting devices comprising a rotatably mounted shaft upon which a plate is borne, a weight hung from the shaft and tending to rotate the shaft under gravity, a stop limiting the rotation of the shaft, and means for controlling the turning of the said shaft, such means including a member reciprocated by the tube-engaging and transporting means and in coordination with the movement thereof, the said controlling means moving in alternation with the movements of said tube-engaging and transporting means.

17. The structure of the next preceding claim, the controlling means being in the form of a slotted bar interengaged with the weight-carrying shaft in an interengagement that permits of lost motion.

HAROLD H. SNYDER.
